BURIAL LOWERING DEVICE
 James E. Mead, 28 Burgess Place, Wayne, N.J.
 Filed Jan. 17, 1962, Ser. No. 166,832
 2 Claims. (Cl. 27—32)

This invention relates to a burial lowering device and more particularly to such devices wherein shaft housings are provided for rotatably journaling shafts in parallel relation therein.

In such devices, the shaft housings are secured together with the rotatable shafts defining therewith a parallelogram; the assembly is usually positioned in registry with or parallel straddling relation to the grave prior to the burial ceremony, the coffin being then positioned over straps secured to the rotatable shafts of the prelocated parallelogram and then by lever or other means on the shaft housings, a mechanism in the housings is triggered to lower the coffin into the grave.

Where burial vaults are provided, the very heavy vault covers have customarily been maneuvered by means of a crane or other mechanism over and then onto the vault after the coffin has been lowered thereinto with the result that the procedure was costly and unsatisfactory, awkward and out of keeping with the dignity of the burial arrangements.

The present invention is designed to obviate the objectionable use of derricks or other extraneous hoisting and lowering mechanisms for burial purposes, the invention providing novel, dignified and efficient means for achieving the ends above mentioned in a rapid, far less cumbersome and in a more convenient fashion.

The drawings, illustrating procedures and devices useful in carrying out the invention, and the description below, are exemplary only of the invention, which shall be deemed to cover all other devices and procedures coming within the scope and purview of the appended claims.

In the drawings, wherein similar reference characters indicate like parts:

FIG. 1 is a perspective view of a burial lowering device embodying my invention, shown positioned in alignment with a grave into which a burial vault cover is to be lowered, pursuant to the invention.

FIG. 2 is an end elevational view thereof, taken at line 2—2 of FIG. 4.

FIG. 3 is a side elevational view thereof, taken at line 3—3 of FIG. 4.

FIG. 4 is the top plan view thereof, taken at line 4—4 of FIG. 1.

FIG. 5 is a fragmentary elevational view thereof, taken at line 5—5 of FIG. 1, and

FIG. 6 is an end elevational view taken at line 6—6 of FIG. 5.

As shown in the drawings, the device of this invention is adapted to utilize a parallelogram unit 10 (FIG. 1) including shafts 11 and 12 rigidly secured to the shaft housings 13—16 and the shafts 17 and 18 rotatably journalled in said housings. The shaft housings 13—16 are provided with any suitable means, such as are well known in this art and described in prior patents, for effecting rotation of the shafts 17, 18 clockwise and counterclockwise as indicated by the arrows 19, 20 (FIG. 1) for winding or unwinding of straps 21, 22 on said shafts.

Any suitable means are provided in the shaft housings 13—16 for achieving the said rotation of the shafts, such as gear means 23 fixed to the rotatable shafts 17, 18 and driven by meshing gear means 24 driven by mechanisms within the shaft housings 13—16, as is well known to those skilled in the art. Suitable control means 25, 26 (FIG. 1) are provided in the housings to lock the shafts 17, 18 against rotation and to actuate the same as desired in

2

either direction as indicated by the arrows 19, 20 (FIG. 1).

Pursuant to the invention, slide track members 27, 28, which may be formed of upwardly opening channels (FIG. 4) are provided, and may be either interconnected for spaced relation or otherwise disposed in spaced parallel relation to each other and to the grave 29 and carrier members 30, 31, 32 and 33 are provided engaging the tracks for movement thereon. Said carrier members are provided with means such as walls 34 which define cup-shaped upwardly extending portions 35 (FIG. 6) on said carrier members 30—33 to removably receive the housings 13—16.

The device may be used in connection with the grave 29 (FIG. 2) and registered therewith. Where, for example, the vault has been positioned in the grave and the coffin lowered thereinto (36, FIG. 4). The device of this invention may conveniently be used to move the vault cover 37 (FIG. 1) from a position adjacent the grave 29 to a position over the same (FIG. 3) and then, by actuating the shafts 17, 18 as by the control means 25, 26, the shafts may be rotated so that the straps 21, 22 (previously secured to the vault cover 37 as through the brackets 38 engaging the handles 39 thereof) the vault cover 37 (previously thus picked up from its position in spaced relation (FIG. 1) to the grave and moved to registry therewith) is lowered onto the vault 36 (FIG. 3). The carrier members 30—33 may be provided with rollers in the form of wheels 41 (FIG. 6) mounted on bearings 42 (FIG. 5) depending from the carrier members 30—33, although it is contemplated that other slidable or rollable interengaging means may be used pursuant to the invention.

Having thus described my invention, what I claim as new and desired to secure by Letters Patent is:

1. A burial lowering device comprising, two track members to be positioned in parallel straddling relation to a grave, two carrier members engaging each of said tracks for movement thereon, recesses formed in the tops of the carrier members, a rectangular lowering unit with shaft housings in each corner thereof, the sides of said unit consisting of four shafts which are supported by said housings, two of said shafts being rotatably journalled within their corresponding shaft housings and extending across the space between said tracks, strap means attached to and extending between said rotatable shafts and adapted to be wound thereon, means for rotating said shafts, said shaft housings being removably carried in said carrier recesses, said track members each comprising a U-shaped channel providing two spaced contact surfaces, and said carrier members each being provided with two pairs of spaced rollers each pair engaged with one of said spaced contact surfaces of said channel.

2. A burial device as defined in claim 1, wherein each of said rollers is peripherally grooved for engagement with said contact surfaces.
